CLAIM

The ornamental design for an undergarment, as shown and described.

DESCRIPTION

FIG. 1 is a front right perspective view of an undergarment showing our new design in an in-use configuration;

FIG. 2 is a front left perspective view thereof;

FIG. 3 is a rear right perspective view thereof;

FIG. 4 is a rear left perspective view thereof;

FIG. 5 is a front right perspective view of the undergarment of FIGS. 1-4 in the in-use configuration shown inside out illustrating the interior thereof;

FIG. 6 is a front left perspective view thereof;

FIG. 7 is a rear thereof;

FIG. 8 is a bottom view thereof;

FIG. 9 is a front view of the undergarment of FIGS. 1-4 in a flat configuration shown inside out illustrating the interior thereof; and,

FIG. 10 is a rear view thereof.

The broken away portion is shown with broken lines to indicate indeterminate length and forms no part of the claimed design. The even-length broken lines, including angled even-length broken lines, shown in the environment of a leg band represents the appearance of environmental stitching and form no part of the claimed design. The uneven-length broken lines and unshaded regions depicting the remainder of the undergarment represent features which form no part of the claimed design.
